Primary Examiner — Lucy Lieberman(74) *Attorney, Agent, or Firm* — Grossman Tucker Perreault & Pfleger(57) **CLAIM**
The ornamental design for an alarm clock capable of playing a plurality of pre-recorded audio tracks, as shown and described.

DESCRIPTION

FIG. 1 is a frontal perspective view of an alarm clock capable of playing a plurality of pre-recorded audio tracks.

FIG. 2 is a rear perspective view thereof.

FIG. 3 is a front elevation view thereof.

FIG. 4 is a rear elevation view thereof.

FIG. 5 is a right side elevation view thereof.

FIG. 6 is a left side elevation view thereof.

FIG. 7 is a top plan view thereof; and,

FIG. 8 is a bottom plan view thereof.

The broken lines in the figures are included for illustrative purposes and form no part of the claimed design.
